UNITED STATES PATENT OFFICE

THEODOR EHRENCBERG, OF NEW YORK, N. Y.

IMPROVEMENT IN RIBBON-BLOCKS.

Specification forming part of Letters Patent No. 144,520, dated November 11, 1873; application filed April 9, 1873.

To all whom it may concern:

Be it known that I, THEODOR EHRENCBERG, of the city, county, and State of New York, have invented a new and useful Improvement in Ribbon-Blocks; and I do hereby declare the following to be a full, clear, and exact description thereof, which will enable those skilled in the art to make and use the same, reference being had to the accompanying drawing forming part of this specification, in which drawing—

Figure 1 represents a horizontal section of my invention. Fig. 2 is a vertical central section of the same.

Similar letters indicate corresponding parts.

This invention consists of a ribbon-block made of a hollow body, with an internal brace supporting the heads, which are inserted into the ends of the hollow body in such a manner that the heads are not liable to be crushed in by the external pressure to which they are exposed in applying the labels and in handling; and by these means a durable ribbon-block of superior lightness is produced.

In the drawing, the letter A designates my ribbon-block, which is composed of a hollow body, a, and heads b b, which are inserted into the ends of said hollow body. The body and head are, by preference, made of pasteboard; and said body may be made in the form of a round or of an oval cylinder, or in any desired form or shape suitable for the purpose for which such block is to be used. In the inte-

rior of the body a I apply a brace, c, which may be cylindrical or in any other form or shape, and which serves to sustain the heads against any external pressure to which the same are exposed in putting on the labels or in packing.

Hollow ribbon-blocks have heretofore been made, and I do not claim such as my invention. Such blocks have the desirable quality of superior lightness, but they lack the requisite durability or firmness. Their heads being fastened to the body only at their edges, and being entirely without support in the middle, are liable to be crushed in by a slight external pressure; and, for this reason, their use has been discontinued.

By my invention the heads are firmly supported, while the weight of the block is but slightly increased; and I am enabled to produce a firm and durable ribbon-block, which is much lighter than the wooden blocks generally used for the purpose of supporting ribbons.

What I claim as new, and desire to secure by Letters Patent, is—

A ribbon-block composed of a hollow body, a, and heads b b, said heads being steadied and supported by an internal brace, c, substantially as shown and described.

THEODOR EHRENCBERG.
